UNITED STATES PATENT OFFICE.

HARRY C. LEONARD, OF GRAND RAPIDS, MICHIGAN, ASSIGNEE TO GRAND RAPIDS
REFRIGERATOR COMPANY, OF GRAND RAPIDS, MICHIGAN, A CORPORATION OF
MICHIGAN.

TRAP FOR DRAIN-PIPES.

1,035,366.

Specification of Letters Patent. Patented Aug. 13, 1912.

Application filed January 14, 1911. Serial No. 602,707.

To all whom it may concern:

Be it known that I, HARRY C. LEONARD, a citizen of the United States of America, residing at Grand Rapids, in the county of Kent and State of Michigan, have invented certain new and useful Improvements in Traps for Drain-Pipes; and I do hereby declare the following to be a full, clear, and exact description of the invention, such as 10 will enable others skilled in the art to which it appertains to make and use the same.

My invention relates to improvements in traps for drain pipes and its object is to provide the same with various new and 15 useful features hereinafter more fully described and particularly pointed out in the claims, reference being had to the accompanying drawings showing a device embodying my invention as applied to a refrigerator, in which drawings,

Figure 1 is a vertical section of a portion of a refrigerator having my improvement therein: Fig. 2 is a horizontal sectional detail of a portion of the same: Fig. 25 3 is an enlarged vertical sectional detail of the drainage pipes and parts adjacent thereto: and Fig. 4 a perspective detail of the lower part of the drainage pipes.

Like numbers refer to like parts in all 30 of the figures.

1 represents the usual rack in the bottom of the ice chamber; 2 the sheet metal bottom of the ice chamber; 3 the air pipe for the escape of cold air downward to the provision chamber below; 4 a drain pipe in the bottom of the ice chamber consisting of a short piece of pipe inserted therein and extending downward therefrom a short distance.

40 5 represents the sheet metal top of the provision chamber, which has its margin extended upward as at 6, whereby any drainage or drip of moisture from the under side of the ice chamber or due to leakage 45 through the bottom 2 of the same will be retained thereon. The bottom of the ice chamber and the top of the provision chamber are slightly inclined rearward to drain the water toward the rear, and the top of the

provision chamber is provided with a short 50 tube 7 to discharge the water from the same and into which tube the tube 4 discharges the water from the ice chamber.

The bottom 2 of the ice chamber is supported upon strips 18 preferably of wood, 55 the ends of which are supported in grooves 8 formed in the interior of the case, and to prevent any water that may reach the same from escaping into the rear groove, a strip 9 of sheet metal 9 folded longitudinally at an 60 obtuse angle is inserted in the groove, extends within the groove opposite the end of the strip 18, and thence is inclined inward and downward and overlaps the inclined edge 6 of the top of the provision chamber and thus serves to receive any water that may run off the strip 18 and discharge the same upon the top of the provision chamber. As a further precaution another strip 10 of sheet metal is folded twice longitudinally as illustrated in Fig. 3 and extends 65 opposite the end of the strips 18 and thence inward above the same and thence upward behind the margin of the bottom of the ice chamber whereby any moisture is prevented from reaching the wood work above 70 the end of the strips 18. Obviously these two strips 9 and 10 may be made integral if preferred.

A drain pipe 11 at its upper end incloses 75 the discharge pipe 7 and extending downward is provided at the lower end with a downwardly extending hood 12 surrounding the same and spaced apart therefrom, which forms the upper half of a chamber or case 80 inclosing the lower end of the drain pipe. The lower half of this chamber is formed of an upwardly open and cup shaped member 13 having an internal shoulder near the top to receive the edge of the hood 12 and 85 support the same together with the drain pipe 11. The upper edge of the cup is flanged outward at 14 and fits closely upon the margin of an opening in the bottom flange 17 of the provision chamber whereby a 90 water tight joint therebetween is formed. This margin is also slightly depressed to provide complete drainage of the provision 95

chamber. I prefer to leave clearance enough between the hood 12 and the member 13 to permit any liquid on the bottom of the provision chamber to escape therebetween. To extend the drainage pipe through the bottom of the refrigerator and securely hold the same and the case member 13 in place, a tube 15 extends downward from the case through the bottom of the refrigerator bearing screw threaded at its lower end, provided with a threaded sleeve 19 which sleeve at its upper end is provided with a conical flange 20 which flange engages the bottom of the refrigerator whereby by turning the sleeve, the flange 20 is forced against the bottom of the refrigerator and securely holds the flange 14 of the case down upon the edge of the lining 17.

To form a trap to prevent cold air from escaping through the drain pipe a cup 16 is provided into which the end of the pipe 11 dips and is spaced apart therefrom. This cup 16 is provided with lugs 21 resting on the inwardly projecting shoulder of the case 13 upon which the hood 12 rests and between which lugs the water from both the bottom lining and the pipe escape. The water coming down the pipe 11 fills this cup 16 and seals the pipe 11 and overflowing the margin of the cup between the lugs escapes downward.

The pipe 11 with the hood 12 is readily removed by lifting the same and swinging the lower end laterally. The cup 16 can then be easily lifted out and thus the device readily taken apart for cleaning.

I do not herein claim the described lining for refrigerators but reserve the same for a separate application in accordance with the requirement of the Office for division.

What I claim is:—

1. A trap for drain pipes, comprising a divided and separable case, the parts of the case being spaced apart to form a passage therebetween, a flange on the upper edge of the lower part of the case to engage the lining of a refrigerator to support the case and direct fluid into said passage, pipes extending oppositely from said case, the upper pipe carried by the case and extending within the same, and a cup in the case inclosing the end of the upper pipe.

2. A trap for drain pipes, comprising a case divided transversely, a flange on the upper edge of the lower part of the case to engage the lining of a refrigerator, a pipe extending downward from the lower part of the case, the upper part of the case detachably supported in the lower part of the same, and spaced apart therefrom to permit fluid to flow from the said lining into the case, a detachable drain pipe ex-

tending through said upper part of the case and supported thereby and a cup supported in the case inclosing the end of the upper pipe and spaced apart from the same.

3. A trap for drain pipes, comprising a lower pipe, a cup on the upper end of said pipe having its upper part of enlarged diameter to form an inwardly projecting shoulder, a hood detachably supported on the shoulder and spaced apart therefrom, an upper pipe extending through the hood and within the cup and supported by the hood, and an inner cup surrounding the lower end of the last named pipe and spaced apart from both the said upper pipe and the outer cup.

4. A trap for drain pipes, comprising a cup having an outwardly extended flange to support the cup and having its lower part of reduced diameter to form an inwardly projecting shoulder below the top, a pipe extending downward from the bottom of the cup, a hood having its lower edge within the top of the cup and supported by the shoulder and spaced apart therefrom, a pipe extending through the top of the hood and having its lower end below the shoulder, and an inner cup having lugs supported upon the shoulder, said inner cup surrounding the lower end of the last named pipe and spaced apart from the same and from the outer cup.

5. A trap for drain pipes, comprising a fixed pipe, a cup on the upper end of said pipe having its lower part of reduced diameter to form an inwardly projecting shoulder below the top, a hood detachably supported on the shoulder and having its lower edge surrounded by the upper part of the cup and spaced apart therefrom, a detachable drain pipe extending through the hood and supported thereby and an inner cup surrounding the lower end of the detachable pipe and supported by the shoulder.

6. A trap for drain pipes, comprising a lower pipe, a cup on the upper end of said pipe having an outwardly projecting flange at the top and an inwardly projecting shoulder below the top, a hood detachably supported on the shoulder, and spaced apart from both the upper part of the cup and the shoulder, a drain pipe extending through the hood and supported thereby and an inner cup surrounding the end of the drain pipe and having lugs engaging the shoulders and supporting said inner cup spaced apart from both the outer cup and the drain pipe.

7. A trap for drain pipes, comprising a lower section of pipe adapted to extend through the bottom of a casing, a cup on

the top of said section of pipe having an inwardly projecting shoulder near the top and an outwardly extended flange at the top, a hood supported by the shoulder and 5 spaced apart from the upper part of the cup, a drain pipe extending through the hood and supported thereby, and an inner cup below the end of the drain pipe, having supporting lugs resting on the said shoul-

der and supporting the hood spaced apart 10 from the shoulder.

In testimony whereof I affix my signature in presence of two witnesses.

HARRY C. LEONARD.
